UNITED STATES PATENT OFFICE.

ALBERT T. VAN ALSTYN, OF NEW YORK, N. Y.

GARMENT-SUPPORTER.

1,305,419.

Specification of Letters Patent.

Patented June 3, 1919.

Application filed September 18, 1914. Serial No. 862,267.

To all whom it may concern:

Be it known that I, ALBERT T. VAN ALSTYN, a citizen of the United States, residing in New York city, in the county of New York and State of New York, have invented certain new and useful Improvements in Garment-Supporters, of which the following is a specification.

This invention relates to and has for its main object to provide garment supporters, which will not break the threads or tear the stocking, having clamps which may be quickly locked or unlocked, and can be with facility manipulated by the mere pressure of the fingers and absolutely prevent the breaking of threads or tearing the stocking.

To this end, a toggle arrangement is provided which is so guided that the mere pressure of a finger is sufficient to lock the same and in turn to unlock the same, and will through the natural tension between the corset and hose automatically lock itself. The novel arrangement consists in a resilient head forming a post against which a slide is clamped the head yielding under such clamping action, the slide being one member of the toggle arrangement; the other member of said toggle arrangement being a lever plate pivoted to a frame; and a limiting stop arrangement whereby, when the lever plate is pressed to clamp the slide against the resilient head and the pivotal connection of said two connections is thereby pressed beyond dead center of the toggle arrangement, said toggle arrangement will be limited in its movement beyond said dead center and be there locked between said dead center and such limiting stop arrangement.

These and other features, capabilities, and advantages of the invention will appear from the subjoined detailed description of specific embodiments thereof illustrated in the accompanying drawings in which—

Figure 1 is a plan view of one embodiment with the resilient head removed therefrom and the slide in line with the lever plate.

Fig. 2 is a cross section of the same along the line x^2-x^2 of Fig. 1.

Fig. 2^a is a front elevational view of the modification illustrated in Fig. 1.

Fig. 3 is an axial section of the same along the line x^3-x^3 of Fig. 1.

Fig. 4 is an axial section similar to Fig. 3 except that the slide is in raised or releasing position.

Fig. 5 is an axial section along the line x^5-x^5 of Fig. 6.

Fig. 6 shows the clamp illustrated in Fig. 1 equipped with the elastic portions of the supporter and the resilient head in clamping position.

Figs. 7, 9, 11, 13, 15 and 17 are fragmentary plan views of a number of modifications embodying the principle of the present invention.

Figs. 8, 10, 12, 14, 16 and 18 are fragmentary axial sections along the lines $x-x$ of Figs. 7, 9, 11, 13, 15 and 17 respectively.

Fig. 19 shows the toggle leverage diagrammatically.

Fig. 20 is a perspective view of the post.

In the embodiment illustrated in Fig. 1 there is provided a frame substantially composed of one piece and comprising a front connecting portion 2, forming one of the clamping jaws or post engaging members, side rails 3, 3 which terminate at their rear ends in upwardly bent loops 4, 4 and a rear connecting portion 8 extending from one rail to the other a short distance forwardly of the loops 4, 4. As particularly illustrated in Figs. 3, 4 and 5, the front connecting portion 2 may be composed of a triple thickness of metal, having an upper portion 2^a and a tongue portion 2^b integral with the upper portion 2^a and bent downwardly between the rails 3, 3 and folded over parallel with the upper portion 2^a to clamp between it and the upper portion 2^a an intermediate portion 2^c, which three thicknesses may be secured to one another by welding or otherwise. The rails 3, 3 are each composed of two parallel sheets of metal, the upper portion 3^a of which, is in a plane with the upper portion 2^a of the front

connecting portion 2, and the lower portion 3^b of which, is integral with the upper portion 3^a and is bent down therefrom so that its front ends fold over the lower surface 5 of the intermediate plate 2^c, its rear ends being pressed together and then looped to form the loops 4, 4, and its intermediate portions between such loops 4, 4 and the connecting portion 2^c, have their upper portions 3^a spaced apart from the lower portions 3^b to form the grooves or guides 15.

The upwardly bent loops 4, 4 form journals for the trunnion pins 5, 5 secured to the sides of the lever plate 6 which has a portion 15 extending rearwardly of the frame 1 provided with lateral extensions 7, 7 having downwardly bent loops 8, 8 forming journals for the inwardly bent pins of the wire 9 to which wire an elastic strip 10, (Figs. 20 5 and 6) is suitably attached by sewing or otherwise.

The lever plate 6 also extends forwardly of the trunnion pins 5, 5 a predetermined distance and terminates in downwardly bent loops 11, 11 spaced apart from one another to accommodate between them the downwardly bent loop 12 of the slide 13, the loops 11, 11 and 12 being in alinement with one another to form a pin bearing for the pivot pin 14. The distance which the plate 6 extends forwardly of the trunnion pins 5, 5 is such as to give proper leverage to the same so as to sufficiently retract the slide 13.

The plate S which extends from the upper portion 3^a of one side rail to the upper portion 3^a of the other side rail is integral with such upper portions and extends forwardly a sufficient distance to form a stop plate to limit the movement, in either direction, of the lever plate 6, which in its forward movement, is at a point that is below the dead center of the toggle leverage.

The front end of the slide 13 is composed of a double thickness, having a portion 13^a folded down and back upon the main portion of the slide, thus forming a rounded surface to come in contact with the stocking when clamped against the resilient post, (Figs. 3 and 4) which portion 13^a has projections 16, 16 one extending from each of its lateral edges, to form slide pins each of which travels in one of the grooves 15, 15. This arrangement of the pins 16 contributes to the good appearance of the article, permitting the upper surface of the slide 13 to be in a plane with the upper surface of the rails 3 and connecting portion 2.

The rear end of the lever plate 6 has a bar 17 formed between the lower ends of 60 the loops 8, 8 (Fig. 2) about which bar 17 the strip 18 passes which has attached to it the resilient post 19.

The resilient post 19 has a head 20 which extends slightly inward to form the sides

21 which are in the line of pressure exercised by the slide 13. The sides 21 are then each bent outwardly to form the base portions 22 which have two transverse slots, one slot 23 adjacent to the head and the other 24 spaced therefrom.

When prepared for use, a strip of cloth 25 is passed around the head and through the slots 23 forming an endless band. Then the strip 18 has one portion of it passed over the upper surface of the edges of the base portions 22, then passed through the slots 24 and under the cloth 25, the strip 18 also forming an endless band, its ends being sewed or otherwise secured to one another so that they will be disposed adjacent to the frame 1, and present a smooth outward surface, see Fig. 5.

In the operation of the device, the hose to be supported has a portion of it 26 placed over the head 20 which head 20 is then positioned between the rails 3, 3 and connecting portion 2, whereupon the forward end of the lever plate 6 is bent down to clamp the slide 13 against the head 20 and so far bent down that its joint or hinge H formed between the slide 13 and lever plate 6 will lie below the point of dead center and be limited by striking the stop plate S; and thus be locked in such position between such point of dead center and such stop plate S. This operation of advancing the slide 13 into clamping position, as will be seen from Fig. 4, may be conveniently done by engaging the joint or hinge H formed between the lever plate 6 and the slide 13 and pressing downward upon the same while at the same time lifting up on the elastic support. The pulling up of the elastic automatically closes or locks the device. When it is desired to release the hose being clamped it is only necessary to exercise slight pressure to break the toggle joint by reversing the action used in locking, which action releases the slide 13 from the post thereby retracting the slide 13 out of engagement with the post 19; or else, similar to clamping operation again manipulate lever plate 6 in the usual manner.

In Figs. 7 and 8 the frame 27 is composed of a single piece of metal having a front connecting portion 28, side rails 29, 29 and a rear connecting portion which is bent up to form a loop 31. The front connecting portion 28 is formed of a double thickness, having a main or upper portion 28^a, and a lower portion 28^b integral with the upper portion and bent down from between the rails 29, 29 and folded over upon the lower surface of the upper portion 28^a. The rails 29, 29 are each composed of two thicknesses of metal, an upper portion 29^a which is in a plane with the upper portion 28^a of the front connecting portion 28 and a lower

portion 29^b which is integral with the upper portion 29^a and bent over adjacent to the upper portion 29^a and spaced apart therefrom to form the guides or grooves 32, the 5 front end portions of which lower portions 29^b being pressed snug against the upper portions which incidentally is the upper portion 28^a of the front connecting portion 28, the ends of the lower portion 28^b being 10 offset to accommodate such front ends of the lower portions 29^b.

The loop 31 receives and forms the bearings for the bar 33 of the lever plate 34, which lever plate is composed of a single 15 piece of sheet metal having three transverse slots therein, one, 42 adjacent to its rear edge and forming the rear bar 35 to which an elastic strip such as the strip 10 illustrated in Fig. 6, may be attached, and two 20 shorter slots 43 and 44 disposed a short distance forwardly of the rear bar 35 and forming between them the bar 33. Forwardly of the slot 44, the plate 34 is provided with a tongue portion 36 looped to form a bearing 25 for the bar 37 of the slide plate 38 which slide plate has a lateral projection 39 one at each side of its forward end which projections travel in the grooves 32. The lever plate 34 just rearwardly of the tongue 36 spreads laterally to form the wings 40 which extend over and beyond the rails 29, 29 and serve as limiting stops for the toggle lever when the slide is advanced into clamping 30 position, the slide 38 operating to clamp a post similar to the post 19 in the modification illustrated in Figs. 1 to 6 inclusive. By and between the rear elongated slot 42 of the lever plate 34 and the rearmost slot 43 of the two shorter slots there is formed the bar 41 to which a cloth strip such as the strip 18 of the modification illustrated in Figs. 5 40 and 6, may be secured.

In Figs. 9 and 10 there is provided a frame 44 similar to the frame 27 illustrated in Figs. 7 and 8 except that the rear connecting portion 45 is bent upward and formed into a loop that extends completely across from the outer edge of one rail 46 to the outer edge of the other rail 47. This 50 connecting portion 45 accommodates the bar 48 of the lever plate 49 forming a pivotal bearing for such lever plate, the bar 48 being formed by and between two transverse slots cut in such lever plate, one slot 50 being 55 an enlarged and elongated slot extending substantially across the rear broad portion of the lever plate and the other slot 51 extending substantially across the forward narrower portion of the lever plate. The 60 forward narrower portion of the lever plate is sufficiently broad so as to extend across the rails 46 and 47 and form a limiting stop for such lever plate. The front end of the lever plate 49 is bent downward and formed

into the loop 52 which accommodates the 65 bar 53 of the slide plate 54. The bar 55 formed by the slot 50 serves as a means to which the elastic strip may be attached.

In Figs. 11 and 12, a modification is illustrated which is substantially identical with 70 the modification illustrated in Figs. 9 and 10 with the exception of the loop on the lever plate forming the pivotal bearing for the slide plate. In this modification, the loop is formed by two tongues 56 and 57, the tongue 75 56 extending from the forward edge of the lever plate and the other 57 extending rearwardly into the slot 51, these two tongues being bent downward and looped to form the required pivotal bearing. The parts in 80 this modification which are substantially identical with parts of the modification illustrated in Figs. 9 and 10 are designated in the drawings with like reference characters and need no further explanation. 85

With the modifications illustrated in Figs. 9 to 12 inclusive, the strip, such as the strip 18 illustrated in Figs. 5 and 6, will be passed over the loop 45.

In Figs. 13 and 14, a modified lever plate 90 and lever plate connection is illustrated. In this modification is provided a rear connecting portion 58 which extends from one rail 59 to the other rail 60 and has lateral ears 61 and 62. The connecting portion 58 is 95 slightly bent upward and the ears then looped to form bearings for the downwardly bent loops 63 and 64 of the lever plate 65. The rear portion of the lever plate 65 is broad and provided with a slot 66 forming 100 a rear bar 67 to which an elastic strip such as the elastic strip 10 of Fig. 6 may be attached. From and between the loops 63 and 64, the lever plate has a narrow portion extending forward, the forward end of which 105 is bent downward into a loop 68 to form a bearing for the bar 69 of the slide plate 70.

Between the ears 61 and 62 the rear connecting portion 58 is bent downward and looped, such rear connecting portion 58 110 having a slot 71 to form a bar 72 to which the cloth strip of a post may be attached.

In this modification, the forwardly extending portion has wings 96, 96 which extend over the rails 59 and 60 thus to form 115 limiting stops for the lever plate.

It will be seen that the rear end of the lever plates in the modifications illustrated in Figs. 7 to 14 are bent downward at an angle. This bend is provided so that the 120 rear connecting bars of the lever plates may be so positioned that when the elastic strip attached thereto is in supporting position and is pulled, it will act to press the lever plate into clamping position. 125

In Figs. 15 and 16, there is illustrated another form of lever plate and lever plate connection. In this modification, the frame

73 is formed similar to the frame of the modification illustrated in Fig. 1, and therefore like parts will be designated with like reference characters without going into the 5 description thereof. Loops 5, 5 accommodate pins 74, 74 formed on the lateral edges of the narrower portion of the lever plate 75. The front end of the lever plate 75 is provided with a tongue which is bent downward 10 into a loop 77 to form a bearing for the bar 78 of the slide plate 79. The plate S here, similarly to the modification shown in Fig. 1, forms a stop for the lever plate 75 against which the front narrower portion 15 of the lever plate strikes. The rear portion of the lever plate 75 is broad, having tongues 81, 81 extending rearwardly from the rear edge of said lever plate and adjacent to the lateral edges thereof. These tongues are 20 bent downward into loops to form bearings for the wire 82 which is bent together to form means to which an elastic strip may be attached. The portion 80 of the wire 82 which is disposed between the tongues 81, 81 25 is slightly bent inward to form an attaching means to which the cloth strip for the post may be attached.

In Figs. 17 and 18, still another form of lever plate connection is provided. In this 30 form, the rails 83 and 84 are slightly bent upward at their rear ends and then bent downward into loops 85 and 86, the lower sides of the loops 85 and 86 being connected to one another by a bar 87 to which a 35 cloth strip for the post may be attached. The loops 85 and 86 form the bearings for the pivot pin 88, the ends of which extend beyond the loops 85 and 86 about which 40 ends, the downwardly bent loops 97 and 98 45 of the lever plate are secured. The rear portion of the lever plate is broad and has extending from its rear edge two tongues, one adjacent to each of its lateral edges, which tongues are bent downward into loops 89 and 90 to form bearings for inwardly bent 50 portions of the wire 91 which wire forms the attaching means for the elastic strip.

The lever plate has a narrow portion extending forwardly between the loops 85 and 55 86 and terminating in a loop 92 which forms a bearing for the bar 93 of the slide plate 94. The narrow forwardly extending portion of the lever plate just rearwardly of the loop 92 spreads laterally to form cam 55 surfaces 95 which serve as limiting stops when the lever plate is in clamping position.

It is obvious that various changes and modifications in the details of construction may be made without departing from the 60 general spirit of the invention.

I claim:

1. A garment supporter having a frame comprising two side members and two end members, one of said end members forming

the post engaging portion, a lever fulcrumed 65 at its intermediate portion to the other end member, a slide plate pivotally connected to one end of said lever plate, the free end of which slide plate forms the other post engaging portion, the post being adapted to 70 enter between said post engaging portions from the underside of said frame, and securing means provided on the other end of said lever plate to which an elastic strip 75 may be attached.

2. In a garment supporter having a post and clamping means to clamp the garment to be supported over said post, said clamping means comprising a frame having a post engaging portion at one end thereof, two 80 side rails, a lever plate fulcrumed at its intermediate portion to the other end of said frame, a slide plate pivotally connected to one end of said lever plate, the free end of which slide plate forms the other post engaging portion and travels between said side rails, and a support on said lever plate to which securing means for said post may be attached, and securing means on the free end of said lever plate to which an elastic 90 strip may be attached.

3. In a garment supporter having a post and clamping means to clamp the garment to be supported over said post, said clamping means comprising a frame having a post engaging portion at one end thereof, two 95 side rails each having a groove on its inner edge, a lever plate fulcrumed at its intermediate portion to the other end of said frame, a slide plate pivotally connected to one end of said lever plate, the free end of which slide plate forms the other post engaging portion, pins on said slide plate traveling in said grooves whereby said slide plate is guided in its movement, and a support on said lever plate to which securing means for said post may be attached, and securing means on the free end of said lever plate to which an elastic strip may be attached.

4. In a garment supporter having a compressible post and clamping means to clamp the garment to be supported over said post, said clamping means comprising a frame having a post engaging portion, two side 115 rails, a lever plate fulcrumed to said frame, a slide plate pivotally connected to one end of said lever plate, the free end of which slide plate forms the other post engaging portion and travels between said side rails, 120 the combined length of said slide plate plus the portion of said lever plate from the point where it connects with said slide plate to its fulcrum point being greater than the distance between said post when not compressed to said fulcrum point so that when said slide plate and lever plate is depressed beyond a straight line, it will lock said post 125

in position, and a support on said lever plate to which securing means for said post may be attached.

5. In a garment supporter having a compressible post and clamping means to clamp the garment to be supported over said post, said clamping means comprising a frame having a post engaging portion, two side rails, a lever plate fulcrumed to said frame, a slide plate pivotally connected to one end of said lever plate, the free end of which slide plate forms the other post engaging portion and travels between said side rails, the combined length of said slide plate plus 10 the portion of said lever plate from the point where it connects with said slide plate to its fulcrum point being greater than the distance between said post when not compressed to said fulcrum point so that when 15 said slide plate and lever plate is depressed beyond a straight line, it will lock said post in position, a support on said lever plate to which securing means for said post may be attached, and securing means on said lever 20 plate to which an elastic strip may be attached.

6. In a garment supporter of the class described, a frame composed of sheet metal having side rails, each side rail having a 30 portion bent back upon itself to form an inwardly facing groove, a post engaging portion connecting the two rails at one end of the frame and also having a portion bent back upon itself and presenting a smooth 35 rounded bent portion to the post to be engaged; loops on the other end of said frame to form bearings, a lever plate provided with pins on its lateral edges and disposed in said bearings, a slide plate pivotally connected to said lever plate, pins on the lateral edges of said slide plate to travel in 40 said grooves to be thereby guided in its movement, and a bar extending from one rail to the other to form a limiting stop for 45 the end of the lever plate which is connected to said slide plate.

7. In a garment supporter of the class described, a frame composed of sheet metal having side rails, each side rail having a 50 portion bent back upon itself to form an inwardly facing groove, a post engaging portion connecting the two rails at one end of the frame and also having a portion bent back upon itself and presenting the smooth 55 rounded bent portion to the post to be engaged; loops on the other end of said frame to form bearings, a lever plate provided with pins on its lateral edges and disposed in said bearings, a slide plate pivotally connected to said lever plate and provided with pins on its lateral edges to travel in said 60 grooves to be thereby guided in its movement, loops on the free end of said lever plate, and a wire supported by said loops

to which wire an elastic strip may be attached. 65

8. In a garment supporter of the class described, a frame composed of sheet metal having side rails, a post engaging portion connecting the two rails at one end of the 70 frame and having a portion presented to the post to be engaged; loops on the other end of said frame to form bearings, a lever plate provided with pins on its lateral edges and disposed in said bearings, a slide plate 75 pivotally connected to said lever plate, loops on the free end of said lever plate, and a wire supported by said loops to which wire an elastic strip may be attached.

9. A garment supporter having a frame 80 comprising a post engaging portion at one end thereof, two side rails, each having a groove on its inner edge, loops on said rails bent upward to form bearings at the other end of said frame, a lever plate pivotally 85 mounted in said bearings, a slide plate pivotally connected to said lever plate, the free end of which slide plate forms the other post engaging portion, pins on said slide plate traveling in said grooves whereby said slide 90 plate is guided in its movement, the grooves in said side rails being disposed in a plane below the axial center of said bearings so that the pivotal connection of said lever plate and said slide plate will be disposed 95 below the imaginary straight line extending from said bearings to said post engaging end of the slide plate, and a bar extending from one rail to the other to form a stop below the pivotal connection of said lever plate with 100 said frame so that after said slide plate has been moved into clamping position the lever plate may be pressed down just below dead center, there limited from further movement, and thus lock said slide plate in clamp- 105 ing position.

10. In a garment clasp, a post and a post receiving frame, post clamping means having one end slidably and pivotally guided in said frame for movement into and out 110 of clamping position, and a strap attaching member pivoted to said frame intermediate its ends and having one end pivoted to the free end of said clamping means, the remaining end of said member being secured 115 to the supporter strap whereby tension on said strap moves said means into clamping position.

11. In a garment clasp, a post and a post receiving frame, post clamping means having one end slidably and pivotally guided on said frame for movement into and out of clamping position, and strap attaching means having swinging articulation and pivoted at one end to the free end of said 120 clamping means, the remaining end of said attaching means connecting with a strap whereby tension on said strap articulates 125

said attaching means and thereby moves said clamping means to a clamping position.

12. A garment supporter having a compressible post, a frame comprising a post 5 engaging portion, two side rails, each having a groove on its inner edge, a lever plate fulcrumed to said frame, a slide plate pivotally connected to said lever plate, pins on said slide plate traveling in said grooves to 10 guide the slide plate in its clamping movement, the length of said slide plate plus the distance from where it is pivoted to the

lever plate to the lever plate fulcrum being greater than the distance from the uncom-pressed post to said fulcrum whereby when 15 the pivotal joint between said slide plate and said lever plate is depressed below a straight line the slide plate will be yieldably locked in clamping position.

ALBERT T. VAN ALSTYN.
